United States Patent

Des. 236,603
Patented Sept. 2, 1975

236,603

PALLET

Dennis M. Melnick, R.D. 1, and Mark Kubick, Brookside
Drive, both of Baden, Pa. 15005

Filed July 5, 1973, Ser. No. 376,455

Term of patent 14 years

Int. Cl. D9—99

U.S. Cl. D12—53

FIG. 1

FIG. 2

FIG. 1 is a top isometric view of a pallet showing our new design; and

FIG. 2 is a bottom isometric view thereof, turned over and rotated 180° to show the end and side opposite to those shown in FIG. 1.

We claim:

The ornamental design for a pallet, as shown.
